UNITED STATES PATENT OFFICE.

HENRY S. JUDD AND HENRY PLETSCH, OF CHICAGO, ILLINOIS, ASSIGNEES TO
JUDD LAUNDRY MACHINE COMPANY, OF CHICAGO, ILLINOIS, A CORPORA-
TION OF DELAWARE.

DRIVING MECHANISM FOR WASHING-MACHINES.

1,240,801.

Specification of Letters Patent. Patented Sept. 18, 1917.

Application filed March 10, 1910. Serial No. 542,388.

To all whom it may concern:

Be it known that we, HENRY S. JUDD and HENRY PLETSCH, citizens of the United States, residing at Chicago, in the county of Cook and State of Illinois, have invented a certain new and useful Improvement in Driving Mechanism for Washing-Machines, of which the following is a specification.

Our invention relates to improvements in washing machines and is illustrated in the accompanying drawing, wherein—

Figure 1 is an elevation with parts broken away;

Fig. 2, a section along the line 2—2 of Fig. 1;

Fig. 3, a detail section along the line 3—3 of Fig. 1.

Like parts are indicated by the same letter in all the figures.

20 The tub A provided with the cover A¹ and locking thumb screw A² has at one end the approximately triangular frame A³ which is provided at the bottom with the projection A⁴ having at the outer end the trunnion

25 A⁵ adapted to rest upon the supporting hanger B which is supported by the frame B¹. The gear segment C is an integral part of the projection A⁴ and engages the segmental gear C¹ which is mounted upon the

30 pin C², which is supported by the arms C³ upon the frame B¹. The lever D is attached by the screws D¹ to the segmental gear C¹ and supports at its upper end the block D² which slidably engages the rod E. The

35 springs E¹ E² surround the rod E and are held between the block D² and the collars E³ E⁴ which are adjustably held upon the rod E by means of the set screws E⁵. The

40 crank F integral with the sleeve F¹ is rotatably mounted upon the driving shaft F² and carries the crank pin F³ which engages one end of the rod E. The sleeve F¹ is carried in the bearing F⁴ and provides a bearing for one end of the shaft F². The

45 jaw G integral with the sleeve F¹ is adapted to be engaged by the jaw G¹ slidably mounted on the shaft F², and held against rotation thereon by the feather G². The jaws

50 G, G¹, are provided with the inclined teeth G³ which however have at their apexes the square tooth members G⁴ adapted to engage corresponding square recesses G⁵ at their bases. The jaw G¹ has the annular groove H thereabout. The lug

H¹ which depends from the rack H² is 55 adapted to engage said groove H. The rod H³ carried in the bearings H⁴ and H⁵ which are supported on the frame B¹, is provided at one end with the hand wheel H⁶ and at the other with the pinion H⁷ to engage the 60 rack H². The lugs H⁸ upwardly extending from the rack H² have the slot H⁹ adapted to engage the rod H³ to support the rack H². By means of the rod H³, and the rack and pinion controlled thereby, the jaw G¹ can be 65 shifted into and out of engagement with the jaw G, to thereby connect and disconnect the operating crank arm F and the shaft F², it being understood that said shaft is rotated from any suitable source of power. 70

The springs K are attached at their outer ends to the studs K¹ and wedge-shaped nuts K² which bear upon the plates K³ on the frame B¹, and are attached at their inner ends by means of the pins K⁵ to the frame 75 A³ in a line with the axis of the tub.

It will be understood that the power is applied to and rotates the shaft F². Such power, of course, would be applied to the shaft F² by means of a gear or pulley or 80 direct connection to the driving shaft of any motor. These being perfectly familiar and obvious means of communicating power to the shaft F², we have not thought it necessary to describe or illustrate the same. The 85 shaft F² being thus rotated carries with it naturally the crank F which reciprocates the bar E, thus rocking the lever D whereby the segment C¹ is rocked about its axis, and since it engages the segment C on the side of 90 the tub, the tub will thus be moved back and forth or oscillated.

This means for communicating motion to the tub together with the other attachments connected therewith and with the tub is 95 operative for the full performance of its function only in connection with an oscillating horizontally supported laundry tub or the like because the motion of the mobile contents of the tub conspires with the parts 100 of the apparatus to bring out the desired result.

We have illustrated in the drawings an operative device, but it will be evident that many changes may be made without departing materially from the spirit of our invention. We wish, therefore, that our drawings be considered as diagrammatic. 105

The use and operation of our invention are as follows:—

The tub illustrated is the usual washing tub supported upon an axis below the center 5 of gravity and maintained in a vertical position by means of a plurality of springs. The tub is oscillated by means of a gear which is mounted about the supporting trunnion and engages a further gear which 10 is oscillated by means of a lever. The lever is driven by a reciprocating rod which in turn is driven by a crank or eccentric. The motion of this rod and lever sets up, of course, the usual oscillation in the tub. This 15 oscillation, however slight, is accentuated by the rush of material to the down side. Since the excursion of the reciprocating rod and oscillating lever is limited, the tub will of necessity be brought up short in its excursion, and the motion of inertia of the tub 20 and the material therein must be carried and reversed in direction by means of the reciprocating machinery. This of necessity causes very considerable shocks upon the 25 machinery at the end of each stroke. These shocks, if not taken up by some flexible connection, are very harmful to the tub and the machinery. In order to take up these 30 shocks a plurality of springs are interposed between the reciprocating rod and the oscillating lever, the result of which is to allow the springs to gradually bring the tub to rest and reverse its direction instead of compelling the strain to come violently upon the 35 driving mechanism. We thus provide a spring rod connection between the tub and the driving power.

We claim:—

1. In an apparatus of the character described, the combination with a main frame, 40 of a body pivotally mounted on said frame to oscillate about a horizontal axis adjacent the bottom of said body, and an oscillating spring pivotally connected at its 45 outer end to said frame and pivotally connected at its inner end directly to said body, said spring being arranged at an angle to the path of movement of its inner pivoted end.

2. In an apparatus of the character de-

scribed, the combination with a main frame, 50 of a body pivotally mounted on said frame to oscillate about the horizontal axis arranged below the center of gravity of said body, counter-balancing springs pivotally connected at their outer ends to said frame 55 and pivotally connected at their inner ends directly to said body on opposite sides of and spaced apart from said horizontal axis, each of said springs being arranged at an angle to the path of movement of its inner 60 pivoted end, a power shaft and driving connections between said shaft and said body comprising a rotary crank and pitman, an oscillating lever and cushioning springs, substantially as described. 65

3. In apparatus of the character described, the combination with a main frame, of a body mounted on said frame and arranged to oscillate about a horizontal axis below its center of gravity, mechanism for oscillating 70 said body about said axis comprising a lever pivoted on said frame below the axis of said body and connected to the latter, a power actuated pitman for oscillating said lever and spring mechanism arranged to coöperate with said lever in effecting the reversals in the direction of movement of said oscillating body, substantially as described. 75

4. In apparatus of the character described, the combination with a main frame, 80 of an oscillatory body, horizontally arranged trunnions adjacent the bottom of said body, bearings at each side of the main frame for said trunnions, springs connected to said body and to the main frame for 85 yieldingly holding said body normally in upright position, a lever connected to the lower portion of said body at one end for oscillating the same, a power driven pitman, a block slidably mounted upon said pitman, and connected to the upper end of said lever, and cushioning springs mounted upon said pitman at opposite sides of said block. 90
